CONTAINER CONSTRUCTION

Edward N. Burnett, San Lorenzo, Calif., assignor
to Gerber Products Company, Fremont, Mich.,
a corporation of Michigan

Application January 28, 1950, Serial No. 141,150

12 Claims. (Cl. 229—23)

1

This invention relates to an improved container construction. Reference is made to my co-pending application Serial Number 112,886, filed August 29, 1949, for Container Construction, now abandoned and of which this application is a continuation-in-part.

The particular embodiment of my invention which is illustrated in the drawings and which will be described hereinafter in greater detail comprises, generally, a pair of closed identically formed box units, each of which is provided with mutually interlocking parts to permit the two individual box units to be locked together to form a unitary box construction. As will hereinafter appear each of the individual box units may be formed from one integral blank of material, such as corrugated cardboard or the like.

In the shipment of certain types of goods and particularly goods contained in relatively small cans or bottles, such as baby foods, medicines, etc., it has generally been the custom to package the goods in inner cartons or containers and to place several of these inner cartons within a relatively larger and sturdier outer shipping carton or case. Obviously, such practices require the utilization of considerable material in making both inner and outer cartons, and, moreover, considerable labor and equipment is involved just in packaging the goods for shipment.

Recently there have appeared on the market several types of box constructions designed to obviate the necessity of employing both inner and outer containers. One type of box construction, for example, comprises two individual box units made of relatively heavy gauge paperboard material (such as is normally employed in conventional outer cases or containers) which are glued to a heavy paper pad and held together at their tops with a seal formed of similar material. Two box units so assembled form a unitary two section container.

Another similar type of box construction consists of two partitioned box units stitched together adjacent their bottom extremities by two strips of suitable material and held together at their tops by a glued or stitched seal or pad. In each of the above instances the pads, strips and seals are separate pieces from the box units which they are adapted to join together.

The present invention provides an improved box construction which utilizes two individual and completely closed box units provided with mutually interlocking members to affix them rigidly and securely to one another. A double wall forming a central partition is established by the

2

joining and interlocking of the two box units together. It is contemplated that a packer or shipper will pack each individual box unit with a predetermined number of cans or bottles and after each unit is fully packed the units will be paired off and locked to one another to form the larger size unitary box constructions.

The advantages of such shipping container made up of a plurality of individual box units interlocked together are numerous. In the first place, a shipper or manufacturer of canned or bottled goods can ship the larger containers to warehouses or central distributing points, and because of the fact that each of the shipping containers is made up of a plurality of individual box units interlocked together, the warehousemen or distributors may divide the larger box constructions into their component box units and sell to retailers or customers in box unit lots if so desired. The interlocking means are such that it is a relatively simple matter to split the units apart by cutting through the material forming the said interlocking means, and, moreover, the entire construction is designed to permit the separation of box units one from the other without causing them to open or in any way exposing the packed contents to dust and deterioration and/or damage in further transit.

Another advantage of the present box construction is that the individual box units are of themselves made of relatively heavy outer casing material and can withstand reshipment and rough handling which goods packed in conventional inner cartons or containers could not withstand.

Another advantage that the present box construction affords is that retailers can divide a shipping case into its component individual box units as heretofore suggested and place only the contents of a single box unit on the shelf at one time if so desired. The emptied box unit can be disposed of and no space is wasted by having to store half empty cases or cartons. Further, the unpacked products are maintained in clean condition during prolonged storage and prior to final retail display. Also, a retailer may sell the contents of a single box unit to a customer for convenient transportation.

The principal object of the present invention is to provide a box construction comprising a number of individual closed box units which, in turn, are provided with mutually interlocking parts to permit the secure joinder of at least two such units together to form a relatively larger unitary shipping case or the like.

Another object of the present invention is to provide a box construction which may be manufactured without having to employ special casting equipment, such as stitching machines or the like.

Another object is to provide a box construction which utilizes a minimum quantity of material. It has been found, for example, that only about one-half as much material is required to make a finished box construction according to the present invention as is required to make a comparable size shipping container according to conventional practice wherein both inner and outer cartons are employed. Moreover, a savings in material results in a saving by weight, and a shipper using the present box construction will benefit by substantial savings in shipping and freight rates based on weight. Less glue and ink are required to seal and print the container which is the subject of this invention than when both inner and outer cartons are employed.

Another object of the present invention is to provide a box construction wherein each individual box unit is formed from one integral piece or blank of material, thus eliminating the necessity for fabricating a plurality of separate box parts, such as pads or stitching strips or the like. A particular disadvantage in manufacturing box units from a plurality of separate and non-integral parts is that more equipment generally is required to produce the individual parts and to assemble and fabricate the parts into finished box units.

Another object of the present invention is to provide a box construction of the type hereinabove characterized which when not in use may be stored as a substantially flat blank thereby resulting in a saving of storage space.

Another object of the present invention is to provide a box construction which is particularly adaptable for relatively simple and inexpensive manufacture.

The ease of packing and forming a plurality of box units into an interlocked container for shipment and/or storage is a principal advantage of the invention. It has been found through actual experience that the amount of equipment and labor necessary to pack and ready the new package for shipment according to the present invention is approximately 50% less than required to pack and ready conventional shipping containers which incorporate both inner cartons and outer casings.

Further objects of the present invention will become apparent upon reading the following specification and referring to the accompanying drawings in which similar characters of reference represent corresponding parts in each of the several views.

In the drawings:

Fig. 1 is a plan view of a blank from which a box unit is formed.

Fig. 2 is an exploded view in perspective of the box construction comprising two individual box units, and showing portions of each unit broken away.

Fig. 3 is a perspective view of the box construction comprising two box units interlocked together and showing certain parts broken away.

Fig. 4 is a plan view of a blank from which a modified box construction may be formed.

Fig. 5 is an exploded view in perspective of the modified box construction of Fig. 4.

Fig. 6 is a plan view of a blank from which another modified box construction may be formed.

Fig. 7 is an exploded view in perspective of the modified box construction of Fig. 6, and showing certain parts broken away.

Fig. 8 is a perspective view of the modified box construction of Fig. 7 comprising two box units interlocked together.

Fig. 9 is a schematic view showing means for closing the box constructions shown in Figs. 6 to 8.

Referring now more particularly to the drawings there is illustrated a unitary box construction or shipping carton, indicated generally at A, comprising a pair of individual closed box units, indicated generally at B and C, respectively, which, in turn, are adapted to be securely interlocked together in a manner to be described hereinafter in greater detail.

The pattern cut-out or blank of material out of which each individual box unit may be formed is illustrated in Fig. 1. The blank may be formed of any suitable and adaptable shipping container material, such as corrugated cardboard or the like. The blank may be considered as comprising essentially four principal central panels indicated at 1, 2, 3 and 4, respectively, and eight flap members which are identified respectively at 5, 6, 7, 8, 9, 10, 11 and 12.

More specifically, the blank is provided with a pair of longitudinally extending parallel score lines 13 and 14. Transverse slits 15 and 16 are formed in the blank and each extends inwardly from the left edge of the blank to the score line 13. Transverse slits 17 and 18, similar to slits 15 and 16, extend inwardly from the right edge of the blank to score line 14. Angular cut-outs 19 and 20 are formed in the blank and extend inwardly from the left and right edges of the blank, respectively, to meet score lines 13 and 14, respectively.

Spaced transverse score lines 21 and 22 extend in straight lines between slits 15-17 and 16-18, respectively. Score line 23 extends transversely across the blank between cut-outs 19 and 20.

It is thus readily seen that the arrangement of the various slits and score lines above identified define the various panel and flap members numbered 1-12 inclusive, in the drawings, and previously mentioned hereinabove.

All of the panels are of the same width, but panels 1 and 3 which are of equal length are shown as being slightly shorter than panels 2 and 4 which, in turn, are of equal length.

The outer ends of flaps 5 and 6 project beyond the outermost edge 1^a of panel 1 to form ears 25 and 26. The inner edges 25^a and 26^a preferably are cut so as to diverge outwardly from score lines 13 and 14 at approximately a 50° angle. Preferably, edges 19^a and 20^a of angular cut-outs 19 and 20 are cut along lines paralleling edges 25^a and 26^a, respectively, of the ears.

To assemble a pair of box units various series of operations may be performed. One series, which is particularly desirable if the containers are used to pack glass containers, entails the following steps:

(A) The blank of each unit is folded at successive 90° angles along score lines 21, 22, and 23. This operation will bring the outer edge 1^a of panel 1 into contact with the outer edge 4^a of panel 4 and the four panels will define a rectangle in plan view. A strip of adhesive tape 27 or other suitable attaching member may be applied to hold the joined edges of panel 1 and panel 4 together.

(B) Pairs of units are grouped together and

panels 4 of each of a pair of units are brought into juxtaposition.

(C) Flaps 8 and 12 of each unit are folded at a 90° angle with respect to panels 2 and 4.

(D) Glue is applied to the undersides of panels 6 and 10 of each unit.

(E) Panels 6 and 10 of each unit are folded at a 90° angle with respect to panels 1 and 3 to overlie and adhere to panels 8 and 12.

(F) Each unit is filled with empty containers at the container factory.

(G) Flaps 7 and 11 and then flaps 5 and 9 of each unit are folded down, but not glued.

(H) Boxes are shipped to the cannery when empty containers are removed, filled and then replaced in the box units.

(I) Flaps 7 and 11 of each unit are folded down.

(J) Glue is applied to the undersides of panels 5 and 9 of each unit.

(K) Flaps 5 and 9 of each unit are folded down at a 90° angle with respect to panels 1 and 3 to overlie and adhere to panels 7 and 11.

Another series of operations to assemble a pair of box units, which is preferable for packing metal containers, entails the following steps:

(A') The blank of each unit is folded at successive 90° angles along score lines 21, 22 and 23. This operation will bring the outer edge 1^a of panel 1 into contact with the outer edge 4^a of panel 4 and the four panels will define a rectangle in plan view. A strip of adhesive tape 27 or other suitable attaching member may be applied to hold the joined edges of panel 1 and panel 4 together.

(B') The bottom of each unit is folded together temporarily by folding down flaps 8 and 12 and then flaps 6 and 10. No glue is used at this time.

(C') Each unit is filled with containers.

(D') Pairs of units are grouped together and panels 4 of each of a pair of units are brought into juxtaposition.

(E') Flaps 7 and 11 of each unit are folded down.

(F') Flaps 6 and 10 of each unit are unfolded, the contents of the box units being supported by flaps 8 and 12.

(G') Glue is applied to the undersides of each of flaps 5, 6, 9 and 10 of each unit.

(H') Flaps 5, 6, 9 and 10 of each unit are folded down. Flaps 5 and 9 of each unit overlie and adhere to panels 7 and 11. Flaps 6 and 10 of each unit underlie and adhere to panels 8 and 12.

Figs. 2 and 3 are illustrative of how two fully packed box units B and C may be moved into interlocked relationship with respect to one another to form a unitary box construction A. These figures also illustrate how angular cut-outs 19 and 20 of each box unit are proportioned to form niches or recesses, such as indicated at 30 and 31 to receive the ears of an adjoining box unit.

The advantages of shipping canned or bottled goods in containers of the character herein described has already been discussed in considerable detail. As has been mentioned, it is sometimes expedient or desirable for warehousemen, distributors or retailers after initial shipment of the goods to divide a shipping carton into its component box units. In Fig. 3 dotted lines 28 indicate the line along which the box construction should be cut. It is noted in this respect that a cut along the indicated dotted line would

sever box units B and C from one another at the point of juncture between adjoining side walls 4 of the interlocked box units. Thus, each box unit when severed from its mate in the above manner will remain wholly intact and closed and may, if desired, be reshipped without having to repack its contents or reinforce the box unit in any way.

Further, unit B may be opened and the contents dispensed, while unit C remains sealed, the contents of unit C during this interval being protected from dirt and other conditions which might affect the merchantability of the product.

Referring now particularly to Figs. 4 and 5 there is illustrated a modification of the container construction which, it is seen, comprises two interlocking individual box units, indicated generally at D and E.

The blank of material from which the modified box construction is formed is illustrated in Fig. 4 and resembles the blank construction illustrated in Fig. 1 in that there are formed four central panels identified at 101, 102, 103 and 104, respectively, which are defined by a pair of parallel left and right longitudinally extending score lines, 113 and 114, and three transverse score lines 121, 122 and 123.

The flaps identified at 107, 108, 111 and 112 are similar to flaps 7, 8, 11 and 12 of the blank shown in Fig. 1 and hereinabove described. It is noted that in the modified blank construction no flaps corresponding to flaps 9 and 10 are provided. Flaps 105 and 106 of the modified blank construction are provided with integrally formed 35 projecting ears 125 and 126 having outwardly divergent inner edges 125^a and 126^a. The width of each of the flaps 105 and 106 approximately equals the length of either of the panels 2 and 4, and said flaps 105 and 106 are formed with ear 40 receiving pattern cut-outs indicated at 119 and 120.

The initial folding operations required to assemble a box unit from a blank proportioned according to the construction illustrated in Fig. 4 are substantially identical with the initial folding movements involved in the assembly of a box unit from a blank proportioned according to Fig. 1. More specifically, successive right angle folds along score lines 121 thru 123, inclusive, 50 are effected and the edges of panels 101 and 104 are secured to one another by a strip of gummed tape 127 or other suitable equivalent means. Opposed pairs of flaps 108-112 and 107-111 are then folded at right angles into edge to edge contact with one another to form top and bottom closures for the box unit. Up to this point the steps of assembly of a box unit from a blank proportioned according to Fig. 4 are identical with the assembly steps described with respect 55 to forming a box unit from a blank constructed in accordance with Fig. 1.

After the above folding operations have been effected flaps 105 and 106 may be folded at right angles to overlie the top and bottom closure members 107-111 and 108-112, respectively, and flaps 105 and 106 are preferably securely glued to said closure members. A strip of gummed tape, such as indicated at 131 may be employed to secure the edge of each flap 105 and 106 to an associated end of the box unit.

It is seen that the pattern cut-outs 119 and 120 formed in flaps 105 and 106 present ear receiving niches, such as indicated at 130 and 131, and the purposes and function of these niches are substantially the same as niches 30 and 31.

previously described. The box units D and E may be securely interlocked to one another by gluing the ears of each box unit within their respective ear receiving niches.

Referring now particularly to Figs. 6 to 8, there is illustrated a modification of the container construction which, it is seen, comprises two interlocking box units indicated generally as F and G.

The blank of material from which this type box is formed is illustrated in Fig. 6 and it will be seen that it resembles the blank shown in Fig. 1 except for the reversal of position of certain of the panels together with their connected flap members and the cutting away of corners of two flap members to permit the resultant positioning of the projecting ears. The resultant blank requires less stock for a completed box of the same capacity than that of Fig. 1. Thus there are formed four rectangular central panels, which, proceeding in order from one end of the blank to the other, are identified as 203, 204, 201 and 202. Panels 203 and 201 are substantially of the same size, and panels 204 and 202 are also of the same size. Said panels are defined by longitudinal score lines 213 and 214 and by transverse score lines 223, 222 and 221.

Integral with panel 203 are flap members 209 and 210 with score lines 213 and 214 there between. Said flaps are notched out as indicated by reference numerals 219 and 220, the angle between the edges 219^a and 220^a of said flaps and the projection of transverse score line 223 being about 35°. The notched out areas are for the reception of the projecting ears 225 and 226 of the box with which the box formed of the instant blank interfits and hence the notched out areas are so dimensioned. Thus line 219^a which defines the inner edge of flap 209 extends outwardly in a straight line until it intersects the projection of the outer edge of flap 211, whereupon it extends outwardly perpendicular to line 213 until it reaches a point distant from line 213 about one-half the length of panel 204. Flap 210 is similarly shaped by line 220^a.

Ear 225 constitutes an integral extension of flap 205, associated with panel 201. Said ear is defined by cut line 225^a which extends outward from the intersection of lines 222 and 213 at an angle of about 35° until it intersects the outer edge of flap 211, then proceeds outward perpendicular to line 213 to intersect the outer edge of flap 205. The line 225^a which separates ear 225 from flap 211 thus cuts off one of the corners of said flap. It will be seen that this corner is concealed in the completed box and the material cut away does not adversely affect the strength, appearance or other qualities of the box. Ear 226 is similarly shaped by line 226^a.

The initial folding operation required to assemble a box unit from a blank comprises folding the blank along lines 221, 222 and 223 and securing the abutting edges of panels 203 and 202 together by a strip of gummed tape 227 or other suitable means. Opposed pairs of flaps 208-212 and 207-211 are then folded at right angles into edge to edge contact with one another to form top and bottom closures for the box unit. Thereupon flaps 206-210 and 205-209 are folded downwardly to overlie the top and bottom closure members and are securely glued to said top and bottom closure members in a manner well known in the art.

It will be seen that the cut-out portions 219 and 220 formed in flaps 209 and 210 are properly

shaped to receive the projecting ears 225 and 226. Thus box units F and G may be securely interlocked by gluing the ears of each box unit within their respective receiving niches.

One of the advantages of the last-described modified construction is the fact that less stock is required to make this modification than the others. Another advantage arises in closing the individual box units after filling, as illustrated in Fig. 9. A series of filled box units are carried along at regularly spaced intervals on conveyor belt 230 which is here assumed to be moving toward the left. It is assumed that the bottoms of the box units have been assembled with units F and G in the position shown. The contents have been packed in the box. Paddle 231 is attached to shaft 232, which is caused to revolve in a clockwise direction, as viewed in Fig. 9. Said paddle forces down flap 207 as it revolves, and, because of the notched out portion of flap 211, flap 211 does not interfere with the movement of paddle 231. Flap 211 is then forced down by shoe 233 as belt 230 moves forwardly. The other flaps are then folded down in the usual manner.

Although the present invention has been described in some detail by way of illustration and example for purposes of clarity of understanding it is understood that certain changes and modifications may be practiced within the spirit of the invention and scope of the appended claims. For example, although the expression "closed box unit" is employed in some of the accompanying claims, it will be understood that box units which are apertured for ventilation or other purposes, boxes provided with transparent windows, and other box units specially adapted for specific uses, may be employed.

I claim:

1. A box unit adapted for interlocking with a complementary box unit to form a unitary box construction comprising a hollow rectangular parallelepiped container, and four flaps constituting extensions of side members of said container and closing the top thereof, a first pair of flaps folded downwardly from opposite side edges, a second pair of flaps overlying said first pair of flaps, folded downwardly from opposite side edges and meeting approximately along the center of the top of said container, one of said flaps of said second pair of flaps having a projecting ear extending beyond the confines of said container, and the other of said flaps of said second pair of flaps having a cut-out portion dimensioned and positioned to receive the projecting ear of a complementary box unit.

2. A box unit as defined in claim 1 and wherein the sides of said container are joined along one side edge thereof, said last-mentioned flap of said second pair of flaps constituting an extension of one of the sides of said container joined at said side edge, and the first-mentioned flap of said second pair of flaps constituting an extension of the side of said container opposite said last-mentioned side.

3. A blank for a box unit of the character described comprising four rectangular central panels, alternate panels being substantially equally-dimensioned, and all of said panels having common side edges, each of said central panels having an integral flap projecting beyond each side edge, the flaps along one side of said blank being in consecutive order, a first flap, rectangular in shape, a second flap having a projecting ear extending upwardly at an angle away from said first flap, a third flap generally

rectangular but cut away at one corner to provide stock for said projecting ear and a fourth flap cut away at a corner adjacent said third flap, the cut away portion being of the same shape as the ear of said second flap.

4. A blank as defined in claim 3 and wherein the four flaps along the other side of said blank are formed in the same manner as the four flaps along the first side of said blank.

5. A plural box construction comprising, a first container unit and a second container unit, each of said units comprising a hollow, rectangular, parallelepiped container and having two top and two bottom outer closure flaps folded at right angles inwardly from and constituting extensions of sides of said units, one top outer flap of each unit having an integral projecting tongue extending beyond the confines of its unit, and one outer top flap of each unit having a niche dimensioned and positioned to receive the projecting tongue of the complementary unit, said tongue projecting beyond the same edge of said unit as that edge from which said niche extends inward, the tongue of each unit overlapping and being joined to the complementary unit.

6. A plural box construction according to claim 5 in which the two outer bottom flaps of each unit are formed in the same manner as the two outer top flaps of the same unit.

7. A plural box construction comprising, a first container unit and a second container unit, each of said units comprising a hollow parallelepiped container, closure flaps folded inwardly from and constituting extensions of sides of said units, and a projecting tongue on a first surface of each unit extending outwardly from one edge of the top of said first surface beyond the confines of its unit, said first surface of each unit also being provided with a niche, each said niche extending inwardly from the same edge as that from which said tongue extends outwardly, each said niche being dimensioned and positioned to receive a projecting tongue of the complementary unit, each said tongue overlapping and being joined to a complementary unit.

8. A plural box construction according to claim 7 in which said first surfaces of said units and the respective tongues engaging therewith are coplanar.

9. A box construction according to claim 7 in which each said tongue is formed as an integral portion of the blank of material out of which the box unit from which it projects is formed.

10. A box unit, adapted for interlocking with another box unit to form a unitary box construction, comprising, a closed box structure presenting six substantially flat plane surfaces

comprising top, bottom, and four side forming members, and two substantially identical ears formed as integral portions of the top and bottom surfaces, respectively, of the box structure projecting outwardly in the same direction beyond one of said sides and substantially coplanar with the surface with which they are formed, said top and bottom surfaces each being formed with a niche shaped complementary to an ear, said niches extending inwardly from the same side as that beyond which said ears project.

11. A box construction comprising, a pair of individual closed box units, each said unit having top closure flaps formed by folding extensions of side members, and a projecting ear on the top of each said unit formed as an integral extension of one of the top closure flaps of said unit, each said ear overlapping and being joined to the top surface of the adjoining unit of said pair of units, and in which a top closure flap of each said unit is provided with a niche positioned and dimensioned to receive the projecting ear of the adjacent unit.

12. A box construction comprising a pair of individually closed box units, each box unit formed from an integral blank of material and having bottom, top, end and side forming members, and mutual interlocking means formed as integral portions of the blanks of the material out of which said box units are formed to permit said box units to be interlocked together to form a unitary box construction, said interlocking means comprising a first ear projecting outwardly from a first surface of a first box unit and overlapping and joined to a first surface of an adjoining second box unit and a second ear projecting outwardly from said first surface of said second box unit and overlapping and joined to said first surface of said first box unit, said first surfaces of said box units being substantially co-planar, and wherein a niche located adjacent and co-planar with each projecting portion of each box unit is formed receiving 45 in nested position and filled by a projecting ear of the adjoining box unit.

EDWARD N. BURNETT.
